UNITED STATES PATENT OFFICE.

HENRY C. NICHOLSON, OF MOUNT WASHINGTON, OHIO.

IMPROVED COVER FOR FRUIT-JARS.

Specification forming part of Letters Patent No. 34,976, dated April 15, 1862.

To all whom it may concern:

Be it known that I, HENRY C. NICHOLSON, of Mount Washington, Hamilton county, Ohio, have invented a new and useful Hermetical Cover for the Mouths of Fruit-Jars and other Preserving-Vessels; and I do hereby declare the following to be a full, clear, and exact description of the nature, construction, and operation thereof, reference being had to the annexed drawings, making part of this specification.

The object of my invention is the provision of a simple, cheap, and effective hermetical cover for fruit-jars, &c., which can be easily made or repaired by any tinsmith.

In the accompanying drawings, Figure 1 is an axial section of my improvement. Figs. 2, 3, and 4 are perspective representations of the ring, the cover, and the jar-mouth. Fig. 5 shows a modification of the ring.

A is a jar having around its neck a groove, B, with a beveled upper side, b.

C is a circular disk of "tin," which may be struck up in a suitable die so as for its upper surface, c, to be convex, and so as to have a flange or lip, c', around its margin. From equidistant parts of the cover-margin depend ears D, which widen downward and terminate on their inner sides in spurs d.

E is a gasket of gum-elastic or other suitable material, which, being interposed between the jar-rim and the cover, enables the closure of the joint.

F is a broad and somewhat flaring ring, which, on being pushed down over the ears, acts to press their spurs against the chamfer b, and thus forcibly and with great power to draw the cover tightly down upon the gasket, and thus to close the mouth of the vessel.

It will be seen that when the ring is pressed down until it acts upon the tips 1 of the ears it tends to bend their extremities inward, thus exerting a leverage force in addition to the inclined place or wedge force of the chamfered neck, resulting in a very effectual pinching of the gasket between the jar and the cover.

It will be seen that the inclined planes may be wholly on the jar and the ring, or (as in the present illustration) on the ears in addition, or on either member of the combination in varying forms and degrees to suit the taste of the maker; also, that the ring may be adapted to vessels of different sizes by a form similar to F', Fig. 4, or the equivalent thereof.

I claim as new and of my invention—

The arrangement of beveled neck B b, cover C, ears D d, ring F, and a suitable gasket, the whole being combined and operating substantially as described.

In testimony of which invention I hereunto set my hand.

HENRY C. NICHOLSON.
